CLAIM

The ornamental design for a weigh-in-motion sensor, as shown and described.

DESCRIPTION

FIG. 1 is a perspective view of a weigh-in-motion sensor embodying the new design from above the front left side thereof, broken in the middle to eliminate redundant features.

FIG. 2 is a perspective view from below the rear right side thereof, broken in the middle to eliminate redundant features.

FIG. 3 is a front elevation view thereof.

FIG. 4 is a rear elevation view thereof.

FIG. 5 is a right side elevation view thereof, broken in the middle to eliminate redundant features.

FIG. 6 is a left side elevation view thereof, broken in the middle to eliminate redundant features.

FIG. 7 is a top plan view thereof, broken in the middle to eliminate redundant features; and,

FIG. 8 is a bottom plan view thereof, broken in the middle to eliminate redundant features.

The dashed lines represent environmental structure that is not claimed subject matter.
